MAGNETIC SEPARATOR.

1,136,215.

Specification of Letters Patent. Patented Apr. 20, 1915.

Application filed August 7, 1911. Serial No. 642,613.

To all whom it may concern:

Be it known that we, MYRON DINGS and ROBERT A. MANEGOLD, citizens of the United States, residing at Milwaukee, county of 5 Milwaukee, and State of Wisconsin, have invented new and useful Improvements in Magnetic Separators, of which the following is a specification.

Our invention relates to improvements in 10 magnetic separators, and it pertains more especially to that class of separators in which a magnetic drum or pulley is employed in connection with a conveyer belt, passing over the pulley or drum, and carrying 15 material to be separated.

The object of our invention is to provide a form of pulley construction in which, by avoiding annular, neutral zones, and zones of little attraction, we are able to expose all 20 the magnetite to substantially equal force. Also to provide a form of conveyer belt which, when passing over the magnetic pulley, will cause the magnetite to travel toward the center of the belt, thereby avoiding the 25 tendency of such materials to pass over and under the edge of the belt into direct contact with the poles of the magnetite.

In the following description, reference is had to the accompanying drawings in 30 which—

Figure 1 is a side elevation of the magnetic separator, embodying my invention. Fig. 2 is a detail plan view of the end portion of the same at which the magnetic pulley is located. Fig. 3 is an enlarged detail view in side elevation of the magnetic pulley, and a portion of the belt, showing a receiver for the magnetite in operative relation thereto, said receiver being partially 35 illustrated in section. Fig. 4 is a detail view of the magnetic pulley with some of the non-magnetizable collars removed to show the arrangement of the pole pieces and magnetic gap. Fig. 5 is an enlarged longitudinal section view of one end portion of the magnetic pulley.

Like parts are identified by the same reference characters throughout the several views.

50 The pulley shaft 1 is provided with a series of radially extending disks 2, which serve as pole pieces, the magnetic coils being so wound upon the shaft between such pole pieces or disks, that said pole pieces

will be alternately of opposite polarity. 55 Near their outer margins these pole pieces are provided with flanges 5, and the free margins of these flanges are curved in a sinusoidal line. The opposite edges of the flanges 5 are parallel, and the space between 60 the margins of said flanges constitutes a sinuous gap 6 of uniform width. The gap 6 may be an air gap, or it may be filled with solid non-magnetic material.

The outer or peripheral surfaces of the 65 flanges 5 are cylindrical, and are preferably covered by rings 8, the outer surfaces of which coincide with the peripheral surfaces of the disks 2, the ring 8 and the peripheries of the disks 2, forming a continuous cylinder 70 or drum surface. The inner surfaces of the flanges 5, near their margins, extend convergingly toward the outer surfaces, forming a comparatively thin edge at the gap.

A belt 10 serves as a conveyer for the material to be separated. Such material is fed to the belt conveyer through a hopper 11, or by any other suitable means. The belt conveyer extends over the magnetic pulley above described, and also over a pulley or 80 roller 12, which is preferably formed of wood. The shaft 1 is rotated from any suitable source of power, by a belt or chain 15, and pulley or sprocket wheel 16, the latter being mounted upon shaft 1. The pulleys are rotated so that the belt conveyer travels in the direction indicated by the arrows in Figs. 1, 2 and 3, and the material on the conveyer is carried over the magnetic pulley. The non-magnetic material is permitted to drop vertically from the outer surface of the magnetic pulley, while the magnetite adheres to the belt, while the latter is 85 in contact with the pulley. But as the belt itself is of non-magnetizable material, the magnetite will drop immediately after the belt leaves the pulley surface into a receiver 17. Referring to Fig. 4, it will be observed that it will not be possible for any of the magnetite to pass downwardly over the magnetic pulley or drum, and escape the magnetic attraction by following any one of the gaps 6, for the reason that said gaps are 90 sinusoidal, and at several points in its downward passage, the magnetite will be in close proximity to, or directly over one of the polar flanges 5, and will be attracted thereto. It will also be observed that by covering

105

the polar flanges 5, by non-magnetizable rings 8, while leaving the peripheries of the disks 2 exposed, the magnetic attraction will be substantially equalized over the entire 5 surface of the drum; whereas, if the outer surfaces of the flanges 5 coincide with the peripheries of the disks 2, the magnetic attraction exerted by the flanges would be more intense than that exerted directly by 10 the disks.

To prevent the magnetite from passing to the ends of the magnetic pulley or drum across and underneath the margins of the belt conveyer, we provide the ends of the 15 drum with disk shaped end pieces 9, of non-magnetizable material. We also provide the conveyer belt with magnetizable rivets 20, which are arranged in rows, extending angularly inwardly from the respective side 20 margins of the belt, forming a V-shaped angle along the longitudinal center line of the belt. These rows also extend inwardly and rearwardly with reference to the direction 25 of conveyer movement. None of the rivets 20 are located directly at the belt margins, and therefore, as the rivets pass over the magnetic drum or pulley, the magnetite near the belt margins will tend to collect around the outer rivets, and subsequently 30 when such rivets leave the magnetic drum or pulley, the magnetite will tend to move toward the next rivet which is still in contact with the drum surface. The rivets are, of course, formed of magnetizable 35 material, and are therefore adapted to successively draw the magnetite inwardly toward the apexes of the converging rows. By this arrangement, we have successfully 40 counteracted the tendency of the magnetite to pass outwardly across the marginal edges of the belt into direct contact with the pulley.

Having thus described our invention, what we claim as new, and desire to secure by 45 Letters Patent, is—

1. A magnetic separator, consisting of a supporting member provided with a set of polar projections having exposed annular peripheral flanges, electro-magnetic windings between said polar projections, flanges on said projections partially overhanging said windings, the opposing margins of the flanges being sinuously curved to approach into and recede from an annular zone constituting a magnetic gap between each pair of pole pieces, and non-magnetizable coverings for said flanges and gaps.

2. A magnetic separator provided with a plurality of annular pole pieces of opposite 60 polarity separated by a magnetic gap, extending in a sinusoidal curve adjacent to its

outer surface, the central portion of said gap being continuous in a plane transverse to the axis of the separator, said magnetic gaps and the sinusoidal margins of the pole pieces 65 being covered by non-magnetizable material, and an annular zone being left exposed between the gaps, and constituting a magnetic zone, the covering of the sinusoidal margins of the pole pieces filling portions of the magnetic field of greatest density, to equalize 70 the density of the field adjacent to the periphery of the separator.

3. A magnetic separator, comprising the combination with a support, of a series of 75 pole pieces provided with outer surfaces, flanges projecting laterally from said pole pieces toward those of the adjacent pole pieces, and non-magnetizable shields covering said flanges and coinciding with those 80 of the pole pieces to form a continuous smooth surface, said flanges having their inner surfaces converging outwardly and forming comparatively short edges opposed to the similar edges of the flanges on the 85 opposing pole pieces.

4. The combination of a separating magnet, a conveyer belt for delivering material thereto, and rows of magnetizable projections on said conveyer belt arranged in rows 90 along lines converging inwardly from the margins of the belt and rearwardly with reference to the direction of conveyer movement, said projections being spaced from each other in each row at less distances than 95 the width of the spaces between the rows.

5. A magnetic drum separator, comprising the combination of supports, exciting coils, annular magnetic pole pieces forming a series of narrow peripheral belts separated 100 from each other by annular zones which include the gaps between the pole pieces, said pole pieces being separated from each other by sinusoidal gaps, each traversing one of said zones from side to side, said pole pieces 105 having laterally projecting annular flanges in said zones and bordering said gaps which are sinusoidal in form and said flanges having their inner surfaces converging outwardly toward the periphery of the separator and forming with the outer surfaces 110 comparatively thin edges at the polar gaps, together with a set of annular coverings for the gap zones substantially as described.

In testimony whereof we affix our signatures in the presence of two witnesses.

MYRON DINGS.
ROBERT A. MANEGOLD.
